COMBINED CLOCK FACE AND HANDS

Byron C. Bennett, 1111 W. 11th St.,
Plainview, Tex. 79072

Filed June 20, 1975, Ser. No. 588,666

Term of patent 14 years

Int. Cl. D10—01

U.S. Cl. D10—125

FIG. 1

FIG.3

FIG.2

FIG. 1 is a front elevational view of a combined clock face and hands showing my new design, the rear being flat, plain, and unornamented;

FIG. 2 is a top plan view thereof, the bottom being identical thereto; and

FIG. 3 is a side elevational view thereof, the opposite side being identical thereto.

The coins shown schematically are for illustrative purposes only.

I claim:

The ornamental design for a combined clock face and hands, as shown.
